DESIGN FOR A COMBINED DOMESTIC WASHING MACHINE CASING AND WRINGER

Charles E. Morgenstern, Binghamton, N. Y., as-
signor to Nineteen Hundred Corporation, Bing-
hamton, N. Y., a corporation of New York

Application June 30, 1934, Serial No. 52,403

Term of patent 14 years

To all whom it may concern:

Be it known that I, Charles E. Morgenstern, a citizen of the United States, residing at Binghamton, in the county of Broome and State of New York, have invented a new, original, and ornamental Design for a Combined Domestic Washing Machine Casing and Wringer, of which the following is a specification, reference being had to the accompanying drawing, forming a part hereof, in which:

The figure is a side elevation of a combined domestic washing machine casing and wringer embodying my new design.

The appearance of the machine as viewed from the opposite side is the same as illustrated except that the wringer supporting extension will be located at the left instead of at the right, the control knobs will be at the right instead of the left, and the hose connection at the bottom of the tub will not be visible.

I claim:

The ornamental design for a combined domestic washing machine casing and wringer, as shown and described.

CHARLES E. MORGENSTERN.
